UNITED STATES PATENT OFFICE.

JOHN R. WOOD, OF NEWARK, NEW JERSEY, AND DANIEL CURTIS EPRIGHT, OF SPRING CITY, PENNSYLVANIA, ASSIGNEES, BY MESNE ASSIGNMENTS, TO ABRAM COX STOVE COMPANY, OF PHILADELPHIA, PENNSYLVANIA, A CORPORATION OF PENNSYLVANIA.

MOLD-SHELL.

1,204,528.

Specification of Letters Patent. Patented Nov. 14, 1916.

Application filed October 30, 1913. Serial No. 798,352.

To all whom it may concern:

Be it known that we, (1) JOHN R. Wood and (2) DANIEL CURTIS EPRIGHT, both citizens of the United States, residing at (1) Newark and (2) Spring City, in the counties of (1) Essex and (2) Chester, and States of (1) New Jersey and (2) Pennsylvania, have invented a certain new and useful Improvement in Mold-Shells, of which the following is a full, clear, and exact description, reference being had to the accompanying drawings.

This invention relates to molding devices and more particularly to a retaining shell or "slip-over jacket" such as may be applied to a finished sand mold to retain the same until after the pouring operation.

It is the object of this invention to provide such a shell or jacket that is extremely convenient of application to molds; that will dispense with the use of weights which are commonly employed for the purpose of taking care of the vertical thrust or pressure within the mold, due to the introduction of molten metal thereinto; also to provide a mold shell or slip-over jacket which fits the mold accurately and affords uniform protection, in all directions, against the pressures created within the mold by the introduction of molten metal thereinto, and is not liable to derangement with respect to the mold.

Still further, and more generally stated, the invention may be defined as consisting of the combinations of elements embodied in the claims hereto annexed and illustrated in the drawings accompanying and forming part hereof, wherein—

Figure 1 represents a plan view of a mold having our mold shell applied thereto; Fig. 2 a side elevation of the same with parts broken away; and Fig. 3 an enlarged sectional detail corresponding to the line 3—3 of Fig. 2.

Describing the various parts by the use of reference numerals, 1 denotes the mold shell or casing which may be of any suitable material, metal being preferred. This shell is shown as frusto-pyramidal in shape and is provided with a series of slotted openings 2 in the upper portion, and a series of circular openings 3 in the lower portion thereof. The purpose of these openings is to ventilate the mold, and the two series will

be so arranged that one will be located above 55 and the other below the parting line between the mold sections *a* and *b*, whereby pressure along this parting line will be resisted by the full strength of the shell.

4 denotes a pair of latches which are pivot- 60 ed to opposite ends of the mold shell, each latch having a hooked end 5 which is adapted to pass beneath and support the bottom board 6, whereby the shell not only incloses the mold but forms, with the bottom board, 65 a support wherein and whereby the mold may be transported.

It will be observed that the bottom of the mold shell is bulged outwardly, as shown at 7, providing an outwardly projecting 70 chamber 8 at the bottom of the shell. This construction provides a space for any sand that may be accidentally shaved from the mold during the application of the shell thereto, thus allowing the shell to rest 75 squarely upon the bottom board and to fit the mold uniformly and snugly, without the provision of any lines of weakness along which the molten metal might flow, and thus result in the production of an uneven casting. 80 It will be observed further that the top of the mold shell is provided, on opposite sides thereof, with a plurality of holes 9, which holes are threaded for the reception of machine screws 10, said machine screws 85 securing the cross bars 11 in place. These cross bars extend the full width of the mold shell, and by the arrangement of the holes 9 may be adjusted, as occasion may require, to clear the sprue hole 12. These bars support the upper mold section *a*, against the internal pressure to which it is subjected 90 when the mold is poured and dispense with the weights which are usually employed.

As previously stated, the openings 2 and 3 95 are for the purpose of ventilating the mold and, as will be observed from Fig. 2, they are separated by a solid wall 1 which covers the parting line between the mold sections *a* and *b*, whereby the mold is effectively protected against rupture along its parting line 100 from the internal pressure created by the molten metal.

It is very essential, as mentioned hereinbefore, that the mold shell should accurately 105 fit the mold so that the mold can not yield the slightest degree in any direction. To assure this accuracy, a pattern is made of

the exact shape and size of the molds over which the mold shell is to be used, and by this pattern the mold shell is tested. To facilitate this work, we find it advisable to 5 make the mold shell in sections which may be assembled about the aforesaid pattern and tried and altered until they exactly fit the same.

In the embodiment of our invention 10 shown in the accompanying drawing, each wall of the shell represents one of the sections, and one end of each of the sections is provided with a flange 13 which overlies the adjoining end 14 of the adjacent section.

15 The overlying parts are held together by bolts 15 which have tapered heads 16 that are counter-sunk within the inner face of the end 14, nuts 17 being applied to the bolts 15 for firmly drawing the parts together.

20 It will be seen from an inspection of Fig. 3 that notwithstanding the joints between the various sections, the inner surface of the mold shell is substantially continuous.

Having thus described our invention, 25 what we claim is:—

1. As a new article of manufacture, a mold shell having a substantially open top, bars extending across said top, and connecting means between said bars and said top 30 permitting the said bars to be adjustably secured to the top.

2. As a new article of manufacture, a mold shell having latches pivoted to opposed walls thereof, said latches having 35 projections adapted to engage and project beneath a bottom board, said shell having an outwardly projecting chamber at the bottom of the wall thereof, and bars extending across and adjustably connected to 40 the top thereof.

3. As a new article of manufacture, a mold shell comprising a plurality of sections, means for securing the sections together, latches pivoted to opposed sections,

said latches having projections adapted to 45 engage and project beneath a bottom board, the said board forming with the bottom of each section an outwardly extending chamber, and bars extending across and adjustably connected to the tops of opposed sections. 50

4. A pouring frame for molds having continuous tapered side walls arranged to surround the mold, said frame being open at the top and bottom and having flanges 55 at both the top and bottom and having vertical slots in the side walls; and latches pivotally mounted at opposite sides of the frame and arranged to engage the bottom board when the frame is placed over the 60 mold.

5. As a new article of manufacture, a mold shell having the bottom of its wall projected outwardly, a bottom board for 65 said shell, and means for securing the board to the shell in engagement with the outwardly projecting portion of said wall whereby the bottom board forms a chamber with such portion of the wall.

6. As a new article of manufacture, a 70 mold shell the wall whereof is tapered from the top to the bottom and having its lower end projected outwardly, a bottom board for the said shell adapted to engage the outwardly projected bottom of said wall and to 75 form therewith a chamber, and means for securing the bottom board in engagement with the outwardly projected portion of said wall.

In testimony whereof, we hereunto affix 80 our signatures in the presence of two witnesses.

JOHN R. WOOD.

DANIEL CURTIS EPRIGHT.
